(57) **CLAIM**

The ornamental design for connector for fluids, as shown and described.

DESCRIPTION

FIG. 1 is a perspective view of a connector for fluids;

FIG. 2 is a front view thereof;

FIG. 3 is a side view thereof;

FIG. 4 is a top view thereof; and,

FIG. 5 is a bottom view thereof.

The broken lines depict portions of the connector for fluids that form no part of the claim.
